EDWARD MAINGUET, OF WASHINGTON, DISTRICT OF COLUMBIA.

FLUID-ACTUATED ROTARY MOTOR.

1,362,722.

Specification of Letters Patent. Patented Dec. 21, 1920.

Application filed April 11, 1919. Serial No. 289,286.

To all whom it may concern:

Be it known that I, EDWARD MAINGUET, a citizen of the Republic of France, at present residing in Washington, in the District 5 of Columbia, have invented certain new and useful Improvements in Fluid-Actuated Rotary Motors, of which the following is a specification.

This invention has reference to that class 10 of rotary motors in which the rotor is suitably mounted to turn within a casing having at one side an intake opening for the passage of the driving fluid whose impelling force imparts motion to the rotor and from 15 which casing the source of fluid energy exhausts, after having effected its purpose.

My invention comprehends the production of an effectively operating rotary motor, of the class stated, of a compact and inexpensive construction, in which the coöperating parts are especially designed for acquiring the fluid pressure created forces and transmitting the same in a simple, compact and effective manner for driving purposes.

Another object of my invention is to provide, in a motor of the character stated, a simple and inexpensive arrangement of parts, whereby, when operatively assembled, the whole presents a strong and durable 25 motor.

A further object of my invention is embodied in a peculiar and novel construction of a rotor that includes an inner or hub ring adapted for being fixedly mounted on 30 or to form an integral part of the shaft to be driven, an outer concentric ring and a series of paddle-shaped pistons, the latter being radially mounted (with respect to the shaft bearing) between the inner and outer 35 rings and having means for being rigidly held to constitute, with the inner and outer rings, a unit adapted for being rotated by the impelling fluid, within a casing that envelopes the said motor, the said casing having 40 a fluid intake, at one side, through which the propelling power is injected in an elongated manner, whereby to constantly engage and impel a plurality of the said paddle-shaped pistons, the said casing also having 45 a fluid exhaust in the other side in close relation to the intake.

In its more complete nature, my invention comprehends, in a rotary motor mechanism, a simple and effective means for maintaining 50 a substantially hermetical lubricant seal between the piston and the walls of the

annular piston chamber that is formed between the two half sections of the casing members.

With further objects in view, that will 60 hereinafter appear, my invention consists in the peculiar construction and novel arrangement of parts to be first explained in detail, specifically pointed out in the appended claims and illustrated in the accompanying 65 drawings, in which:

Figure 1 is a side elevation of my improved rotary motor.

Fig. 2 is a top plan view thereof, parts being shown in horizontal section, the intake and exhaust conduits being indicated in dotted lines. 70

Fig. 3 is a partial cross section of my motor taken substantially on the line 3—3 on Fig. 1, and illustrates the manner in 75 which my improved rotor unit is assembled.

Fig. 4 is a horizontal section thereof taken on the line 4—4 on Fig. 3.

In carrying out my invention, I construct the body or motor casing of two substantially circular half sections 1 and 2, each of which includes a practically semi-cylindrical annular seat 3, the opposite edges 4 of each of which merge with annular peripheral channels 5, the reason for which will 80 presently appear.

The casing section 1 is integral with a base 6 and both casing sections 1 and 2 have the usual annular flanges 7 for receiving the clamp bolts 8 that secure the said casing 90 sections together.

The two casing sections 1 and 2 have the usual central or hub bearing for the passage of the driven shaft of which the rotor forms an integral part or is fixedly attached to 95 and from which the acquired power is transmitted for driving purposes, in any suitable manner.

The casing section 1 has a horizontally elongated inlet port 12 and the casing 2 has 100 an exhaust port 13, the latter being of somewhat lesser area than the intake port 12.

By reason of arranging the ports 12 and 13, as stated, with the inlet port 12 elongated across the piston chamber, a plurality of the 105 pistons will, at all times, be in line with the said port 12 (see Fig. 1) and in consequence, fluid entering the port 12 engages a number of the pistons and thus provide a fluid intake force on the pistons of such pressure 110 that the fluid impact is sufficient to impart forward motion to the rotor.

The rotor, the construction of which constitutes an essential feature of my invention, consists of an inner or hub ring 14 that is integral with or keyed onto the shaft 11 to turn therewith, and an outer concentric ring 15. Between the inner and outer rings 14 and 15 is mounted a number of paddle-shaped or circular disk pistons 16, each of which is rigidly connected with the said outer and inner rings 14 and 15, the said disk being of a diameter to snugly fit and travel within the annular or piston chamber 17 that is formed by the opposing semi-circular annular seats in the two opposing casing sections, when the said sections are assembled, as is clearly shown in Fig. 2, by reference to which it will also be seen that the inner hub ring 14 travels within an annular channel 18 formed between the hub portions of the casing sections, while the outer ring 15 is guided and travels in the peripheral or outer channel 5 formed between the outer portions of the casing sections 1 and 2, as shown.

For conveniently mounting the several pistons between and onto the inner and outer rings 14 and 15, I construct the said pistons in the manner best shown in Figs. 3 and 4 which illustrates the piston as composed of two disk members, each of which, at one side, has a half section tapering pintle, the two pintle sections, when the parts are assembled for use, constitute a journal 20 for engaging a corresponding socket bearing 21 in the inner ring 14.

Diametrically opposite the side having the journal 20, the disks, that form the piston, have recesses, which, when the parts are assembled, constitute radial sockets 22.

In assembling the parts, the several pistons are placed on the inner ring 14 by fitting their journals 20 into the socket bearings 21. The outer ring 15 is then fitted over the piston, as assembled on the inner ring 14, with their radial apertures 23 in register with the sockets 22 in the several pistons.

When thus positioned, the pistons and the outer ring 15 are locked into rigid connection by plug or key pieces 24 that pass down through the ring apertures, as indicated by the arrow α , see Fig. 3, and which shows the key piece or plug about to enter into the socket 22 of the piston, Fig. 3, by reference to which it will be noticed the key pieces 24 each have a central lubricant passage 25 which communicates with the lubricant channels 26-26 formed between the meeting faces of the two disk sections that constitute the piston and which communicates with annular spaces 27-27 formed in the peripheral meeting faces of the disk that constitute the piston and with a lubricant inlet passage 28 that passes through the tapering journal which engages the bearing in the inner or hub ring and which, in turn,

communicates with a series of annularly disposed key ports 29 that communicate with a main feed port 30 formed in the driven axle or shaft 11 and into which extends the injecting end of a lubricant feed pipe 31 which connects with a pump 32 adapted for feeding oil under a pressure slightly in excess of the fluid pressure that drives the rotor, as will presently be more fully explained.

By referring now to Figs. 3 and 4 of the drawings, it will be noticed each disk, when the parts are assembled for use, has a pair of oppositely independent spaces 27-27 with which the lubricant passages, in the disk members that constitute the piston, connect.

Each piston is equipped with a pair of independent and oppositely disposed substantially semi-circular packing rings 33, the outer or peripheral faces of which extend between the disk members that constitute the pistons.

Each packing ring member 33 has a flanged head 34 that rides within the spaces 27, the flanges 35 thereof operating to hold the packing rings 33 from becoming detached from the piston and each ring section 33 is constantly forced outwardly by a leaf spring 36 that rests in the spaces 27 and against their respective packing shoes or ring sections 33 and which is constantly submerged by the lubricant that is forced back of the said springs by pump pressure.

Each pair of piston disk sections are held in rigid connections by screws 37-37, as shown.

By connecting the pistons and the rings 14 and 15 in the manner shown and described and by making the inner hub ring 14 as an integral part of the shaft 11, a compact, easily assembled and rigid rotor unit is provided, and, since the said rotor unit is completely enveloped by the casing, it produces a rotor of great strength and rigidity and adapted for rotating while it is substantially hermetically sealed by the constant feeding of the lubricant, under pump pressure, to the parts, as before stated.

By providing a casing firmly mounted on a base, the detail structure is capable of being supported in a steady manner, while the whole interior constitutes a rotor with which the shaft, of which the rotor constitutes a fixed part, turns within the said casing.

By laterally extending the inlet, the propelling or motive power fluid is caused to impact against a number of the pistons at the same time.

The construction just mentioned has been adopted, so the motive power pressing on a few paddles at a time will force them immediately toward the exhaust aperture.

From the foregoing description taken in connection with the drawing, the complete

construction, the manner of operation and the advantages of my invention will be readily understood by those skilled in the art to which my said invention relates.

5 What I claim is:

1. In a rotary motor of the character described, a casing having an annular piston chamber, a rotor, mounted in the casing, that includes a driven shaft, pistons attached 10 to the shaft and projected radially therefrom, the said pistons including members that snugly fit and travel within the aforesaid annular chamber, the said casing having an intake for the impelling fluid, at one 15 side, and an exhausting outlet at the other side, and means for establishing a lubricant seal between the opposing faces of the pistons and the casing.
2. In a rotary motor of the character described, a casing having an annular piston chamber, a rotor, mounted in the casing, that includes a driven shaft, pistons attached to the shaft and projected radially therefrom, the said pistons including members that 25 snugly fit and travel within the aforesaid annular chamber, the said casing having an intake for the impelling fluid, at one side, and an exhausting outlet at the other side, and means for establishing a lubricant seal 30 between the opposing faces of the pistons and the casing, the said means including a lubricant supply pump, a delivery pipe that connects the pump and the rotor, the latter having distributing channels that connect 35 with the supply pipe and deliver the lubricant over the contacting surfaces between the rotor and the casing.
3. In a rotary motor of the class described, a casing having an annular piston chamber formed with inner and outer opposing annular channel ways, said casing having a horizontally elongated intake for the propelling fluid, at one side, and an exhaust outlet at the other side, the said casing 40 having also having an axial bearing that communicates with the annular piston chamber through the inner annular channel thereof, piston blades shaped to snugly fit the annular piston chamber, inner and outer rings 45 that fit and travel in the aforesaid inner and outer channels, means for fixedly mounting the piston blades between the said rings, a driven shaft mounted in the axial bearing in 50 the casing, the inner ring being as an integral part of the said shaft, whereby the shaft, the rings and the piston blades constitute a rotor, the said piston blades including 55 radially expandible packing shoes, and means for constantly holding the said shoes to their 60 extended or packing position.
4. In a rotary motor of the class described, a casing having an annular piston chamber formed with inner and outer oppos- 65 ing annular channel ways, said casing having a horizontally elongated intake for the propelling fluid, at one side, and an exhaust outlet at the other side, the said casing also having an axial bearing that communicates with the annular piston chamber through the inner annular channel thereof, piston 70 blades shaped to snugly fit the annular piston chamber, inner and outer rings that fit and travel in the aforesaid inner and outer channels, means for fixedly mounting the piston blades between the said rings, a driven shaft mounted in the axial bearing in 75 the casing, the inner ring being as an integral part of the said shaft, whereby the shaft, the rings and the piston blades constitute a rotor, the said piston blades including radially expandible packing shoes, and means for constantly holding the said shoes to their 80 extended or packing position.
5. In a rotary motor of the class described, a casing having an annular piston chamber formed with inner and outer opposing annular channel ways, said casing having a horizontally elongated intake for the propelling fluid, at one side, and an exhaust outlet at the other side, the said casing also having an axial bearing that communicates with the annular piston chamber through the inner annular channel thereof, piston 85 blades shaped to snugly fit the annular piston chamber, inner and outer rings that fit and travel in the aforesaid inner and outer channels, means for fixedly mounting the piston blades between the said rings, a driven shaft mounted in the axial bearing in the casing, the inner ring being as an integral part of the said shaft, whereby the shaft, the rings and the piston blades constitute a rotor, the said piston blades including radially expandible packing shoes, and means for constantly holding the said shoes to their 90 extended or packing position, the said means comprising a pair of oppositely disposed substantially annular peripheral spaces into which the inner faces of the shoes extend, a spring located in each of the said spaces for engaging with the inner faces of their respective packing shoes.
6. In a rotary motor of the class described, a casing having an annular piston chamber formed with inner and outer opposing annular channel ways, said casing having a horizontally elongated intake for the propelling fluid, at one side, and an exhaust outlet at the other side, the said casing also having an axial bearing that communicates with the annular piston chamber through the inner annular channel thereof, piston 95 blades shaped to snugly fit the annular piston chamber, inner and outer rings that fit and travel in the aforesaid inner and outer channels, means for fixedly mounting the piston blades between the said rings, a driven shaft mounted in the axial bearing in 100 the casing, the inner ring being as an integral part of the said shaft, whereby the shaft, the rings and the piston blades constitute a rotor, the said piston blades including radially expandible packing shoes, and means for constantly holding the said shoes to their 105 extended or packing position, the said means comprising a pair of oppositely disposed substantially annular peripheral spaces into which the inner faces of the shoes extend, a spring located in each of the said spaces for engaging with the inner faces of their respective packing shoes, and other means for feeding a lubricant, under pressure, through the casing and into the 110 spring contained spaces to discharge against the said springs, whereby to force the said lubricant between the contacting faces of the said shoes and other contacting parts of the 115 rotor and the casing.

EDWARD MAINQUET.
